US00D956893S

(12) **United States Design Patent** (10) **Patent No.:** **US D956,893 S**
(45) **Date of Patent:** **** Jul. 5, 2022**

(54) **SEAT ASSEMBLY FOR WEIGHTLIFTING APPARATUS**

D265,111 S 6/1982 Lynn
D269,691 S 7/1983 Ornstein et al.
D273,334 S 4/1984 Young

(Continued)

(71) Applicant: **Coulter Ventures, LLC.**, Columbus, OH (US)

FOREIGN PATENT DOCUMENTS

(72) Inventors: **Charlie Tighe**, Columbus, OH (US);
Tyler McClure, Galena, OH (US);
Ahmik Jones, Upper Arlington, OH (US)

EP 2400205 A1 12/2011
EP 3295998 A1 3/2018
(Continued)

(73) Assignee: **Coulter Ventures, LLC.**, Columbus, OH (US)

OTHER PUBLICATIONS

(**) Term: **15 Years**

Rogue product advertisement dated Dec. 3, 2015 (redacted).
(Continued)

(21) Appl. No.: **29/754,667**

(22) Filed: **Oct. 13, 2020**

Primary Examiner — Khawaja Anwar

Assistant Examiner — Julice Seung Eun Oum

(51) LOC (13) Cl. **21-02**

(74) Attorney, Agent, or Firm — Banner & Witcoff, Ltd.

(52) U.S. Cl.

USPC **D21/694**

(57) **CLAIM**

The ornamental design for a seat assembly for weightlifting apparatus, as shown and described.

(58) **Field of Classification Search**

USPC D21/690, 694, 668, 676, 675

DESCRIPTION

See application file for complete search history.

(56) **References Cited**

FIG. 1 is a top, front, left perspective view of a seat assembly for weightlifting apparatus showing our new design;

U.S. PATENT DOCUMENTS

FIG. 2 is a front view thereof;

88,047 A	3/1869	Lawrence
D47,725 S	8/1915	Heulings
D47,726 S	8/1915	Heulings
1,410,149 A	3/1922	Williams

4,323,236 A	4/1982	Szabo
D264,756 S	6/1982	Andersson

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top, front, left perspective view of the design in

FIGS. 1-7 shown with example environment.

The broken lines depicting the remainder of the seat assembly for weightlifting apparatus show features that form no part of the claimed design. The broken lines depicting example environment in FIG. 8 form no part of the claimed design.

1 Claim, 8 Drawing Sheets
